4 Claims. (Cl. 200—87)

In rigid contact type relays having more than one operative contact in at least one of the two directions of armature movement, the contacts must be in alignment, that is, there must be substantially simultaneous closure of all, and not just some, of the contacts when excitation reaches a critical value, and the attracting or restoring force applied to the armature must be distributed as between the various contacts. The reason for such alignment is that it is impossible to adjust the contacts satisfactorily when the relay is initially adjusted; also, the contacts may wear unevenly during the life of the relay.

Alignment is usually achieved by means of flexible strips which bear the contacts, but this system, although very common, has a number of disadvantages. The electromagnet and the restoring device must overcome the resilience of one strip for the contact of the next strip to close, but the power required to overcome this resilience is not negligible and increases the current consumption of the relay. If the current is supplied in a progressively increasing or decreasing fashion, the relay armature may stop in an intermediate position in which one contact has been closed but the next contact which should also have been closed has not been closed. The inherent strength of the strips in dependence upon time and temperature is inconstant, with detriment to the accuracy of the relays using such strips. Often, the armature strikes either the attracting pole or appropriate stops at the end of its movement, and so the contact pressure is equal just to the pressure of the flexible strips, and some of the attractive force is not used to provide increased contact pressure.

It is therefore preferred to provide a rigid support for the contacts, more particularly in sensitive precision relays, but means are then required to align the contacts.

According to this invention, in an electromagnetic relay comprising an electromagnetically actuated armature in the form of an elongated plate which is adapted to pivot around a transverse axis, the armature being urged at least in one tilting direction by electromagnetic forces acting in opposite directions on either side of the said axis, the bearings for pivot pins providing the said axis are so devised that the pivot pins can move in a direction substantially perpendicular to the plane of the armature plate, while the armature has, to one side of the said axis and on one surface, a first rigid contact surface and, to the other side of the axis and on the opposite surface of the plate, a pair of second rigid and adjacent contact surfaces arranged symmetrically of a plane which is perpendicular to the axis and which passes through the first contact surface, the three rigid contact surfaces co-operating respectively with three stationary rigid contact elements.

The relay may comprise a C-shaped yoke, the armature being disposed between the ends of the yoke and co-operating at one end with the inside face of the corresponding end of the yoke and at its other end with the outside surface of the other end of the yoke.

The electromagnetic relay thus comprises a number of rigid contacts, contact alignment being achieved while using a reduced power in the relay winding. The invention is therefore particularly suitable for delicate pre-

2

cision relays including those in which the armature is restored by means of a permanent magnet, that is, in which there is considerable mechanical independence as between the yoke and the armature, so that the relay has a high "snap" action in both directions.

Forces acting to opposite hands, on either side of the axis, upon the armature, that is, forces which produce a couple relatively to such axis, can be produced in the release directions of the relay by two restoring devices, which may be permanent magnets or springs, arranged to operate in opposite directions.

The relay can comprise a C-shaped yoke associated with two restoring devices operative to opposite hands so that the armature can be associated with three contact studs in both pivoting directions. With this arrangement, as the armature tilts, that stationary contact which is first encountered by the corresponding rigid contact on the armature acts as a bearing for the armature until further movement thereof leads to it touching, by way of a second rigid contact, a second stationary contact, whereafter the armature in its further movement pivots around the axis defined by these two bearing points until the third contact encounters the corresponding stationary contact, so that the armature is engaged with three fixed contacts disposed in a triangle either by the attracting couple or by the restoring couple.

In this operation the armature starts to move around its pivot axis, then continues its movement by its kinetic energy until the three armature-mounted contacts have engaged with the three stationary contacts, and the ends of the armature axis may move relatively to the yoke.

If the armature-mounted contacts are insulated from each other, three different electric contacts can be operated to either hand of armature movement. *Inter alia*, if the armature-mounted contacts are associated electrically in pairs, the invention leads to the provision of a triple change over switch.

In one simple and advantageous form of the invention in order that the pivot axis may move perpendicularly to the armature plane, the axis is provided by pivot pins which engage in apertures which are elongated in the required direction of movement. Assuming that the contacts are disposed symmetrically of the axis and that there are initially substantially negligible alignment errors, the amount of such elongation should correspond to half the possible contact wear if the armature co-operates with three contact elements only in one of its pivoting directions, but equal to the whole of such wear if the armature co-operates with three contact elements in each of its two tilting directions.

One form of the invention is shown in the accompanying drawings, in which:

FIG. 1 is a perspective view;

FIG. 2 is a longitudinal section; and

FIG. 3 is an end elevation.

The relay illustrated in the drawings is of the kind disclosed in my U.S.A. Patent No. 3,013,136 and comprises a C-shaped yoke 1 formed by two parts abutting each other along an inclined boundary 2 and mounted inside a former 3 for a winding 4 which energises the relay. An armature 7, pivotable around a transverse axis 8, co-operates with an inside surface 5 and an outside surface 6 of the yoke 1. In practice, the axis 8 is provided by two aligned pivot pins 8a and 8b projecting from side edges of the armature 7. The armature 7 is urged in a return movement by a permanent magnet 9 borne by a thickened flange 3a on one end of the former 3. The other end 3b of the former 3 bears a stationary break-contact element 10 which limits the armature return movement produced by the magnet 9; also mounted on the end 3b is a stationary make-contact element 11 which limits

the movement of the armature 7 when the same is attracted by the yoke 1.

Electricity is supplied to the armature 7 by way of a flexible conductor 12 connecting the armature to a bar 13 which provides the bearing for the pivot pin 8a; the bearing for the pivot pin 8b is provided in another bar 23. The current, supplied by way of a connecting part 13a at the end of the bar 13, can flow either through the contact element 10 or through the contact element 11, depending upon the state of energisation of the relay.

The bearings in which the pivot pins 8a and 8b can pivot take the form of apertures 20 which are oval with the major axis in a direction substantially perpendicular to the plane of the armature 7. Alternatively, the pivot pins 8a, 8b can be fitted in miniature ball bearings whose outer races are borne in an oval casing in which the pivot and bearing assembly can move perpendicular to the armature 7. The armature 7 has a hooked end 14 which surrounds the yoke arm 15 which provides the inside attracting surface 5, the hooked end 14 being above and opposed to the magnet 9. The outer corners of the magnet 9 are chamfered in order to concentrate the magnetic force towards the longitudinal axis of the armature 7. The part 14 supports, with the interposition of an insulating strip 16, a conductive strip 17 opposed to two stationary make-contact elements 18 and 19 which extend, after the fashion of gallows, above the part 14.

The device operates as follows:

In the normal position, that is, with the permanent magnet 9 attracting that end of the armature 7 which is on the left in FIGS. 1 and 2, the pivot pins 8a and 8b bear against the bottom edge of the apertures 20, while the opposite end of the armature 7 bears against the stationary break-contact element 10. When the winding 4 is energised, the two surfaces 5 and 6 attract the armature 7 simultaneously so that the armature tilts around its axis 8. Since the attraction provided by the surfaces 5 and 6 is substantially equivalent to a couple, the thrust reaction applied to the axis 8 is negligible. The right-hand end, FIGS. 1 and 2, of the armature 7 moves towards the make-contact element 11, while the strip 17 at the left-hand end of the armature 7 moves towards the two make-contact elements 18 and 19.

If all the stationary contact elements 11, 18, 19 are correctly adjusted, the armature 7 engages with all of them simultaneously and without any movement of the axis 8. If, however, the armature touches, for instance, the contact element 11 first, any further movement of the armature 7 shifts the two pivot pins 8a and 8b upwards in the apertures 20 until the armature engages with the stationary contact elements 18 and 19. If the levels of the elements 18 and 19 are slightly different from one another, the armature 7 pivots around the axis defined by the element 11 and whichever of the elements 18 and 19 it touches first, until contact is made with all three elements 11, 18, 19. Clearly, the armature can perform these various pivoting movements because, the contacts 18 and 19 being close together and in an alignment which is parallel to the pivot 8, the armature can pivot, for instance, around the axis provided by the elements 11 and 18, which latter axis is substantially perpendicular to the axis 8, without any risk of the pivot pins 8a and 8b jamming in the oval apertures 20. Also, tilting of the armature is facilitated by the restoring force of the magnet 9 being localised towards the longitudinal axis of the armature.

In the "make" position the armature rests on the three contact elements 11, 18, 19 disposed in a triangle, while the pivot pins 8a and 8b bear laterally against the long edges of the apertures 20.

In practice, the contact elements 11, 18, 19 are so adjusted in height that, assuming that the armature is infinitely thin, the elements 11, 18, 19 bound a plane disposed very slightly above the bottom edges of the two apertures 20. Consequently, because of the "snap" action

of the armature produced by the magnetic attraction of the yoke 1, and by the permanent magnet 9, the three contacts 11, 18, 19 close substantially simultaneously, or at any rate it is impossible for a contact to stay open while the other two are closed. The snap action and the localisation of the magnetic forces are adequate to overcome bearing friction. Also, the kinetic energy of closure of the contact 11 is partly dissipated in the translational movement of the pivot pins 8a and 8b, thus reducing rebound from the contact 11.

If a return device, operative on the armature 7 in the opposite direction to that in which the magnet 9 is operative, and with a comparable force, is provided at the end near the contacts 10 and 11, for instance, by a permanent magnet being placed above that part of the armature which co-operates with the contacts 10 and 11, a second pair of contacts which are symmetrical of the contacts 18 and 19 in relation to the plane of the armature 7 can be associated with the contact 10, so that three contacts are made during the return movement of the armature.

When, as is the case illustrated in the drawings, the armature touches three contact elements only in one direction of pivoting, the difference between the length of the major axis of the oval apertures 20 and the diameter of normal circular bearing apertures for the pivot pins 8a and 8b need correspond to only half of the maximum possible contact wear, assuming that the initial adjustment for incorrect alignment is negligible, but if, referring to FIG. 2, it is assumed that a pair of contact elements associated with the element 10 are placed opposite the elements 18 and 19 on the other side of the armature, the armature effecting a movement equal to the distance between the elements 10 and 11, the said difference of the apertures 20 must be equal to the whole of the possible contact wear if the pivots 8a and 8b are never to bear against the ends of the oval apertures 20.

In the embodiment illustrated, the armature operates as a changeover device between the contact elements 10 and 11, and as an on-off switch between the contact elements 18 and 19.

The strip 17 can be replaced by two separate contacts insulated from one another and connected externally by flexible conductors similar to the conductor 12. Where three stationary contact elements are used in each direction of pivoting, such contact elements can, in pairs, be changeover contact elements similar to the elements 10 and 11.

The position of the stationary contact elements can be adjusted in any appropriate manner but is preferably adjusted in the manner disclosed by my aforesaid U.S. patent that is, by means of two screws 24 which have frustum-shaped heads and which are parallel and in contact with one another and which are engaged in an elongated aperture in the support for the stationary contact elements.

Of course, the embodiments hereinbefore described can be modified, inter alia by the substitution of equivalent technical means, without for that reason departing from the scope of this invention.

What I claim and desire to secure by Letters Patent is:

1. In an electromagnetic relay comprising an elongated flat armature having two ends and two surfaces, pivoting means for supporting said armature around a substantially medial transverse axis, means providing electromagnetic forces for tilting said armature about said axis in one direction and means for providing restoring forces for tilting said armature about said axis in the reverse direction, at least one of said means for providing forces acting on both said ends of said armature, means for restricting the displacements of said armature when said armature is tilted, a first rigid contact surface carried by one of said ends of said armature on one of said surfaces thereof, two adjacent rigid contact surfaces carried by the other of said ends of said armature on the other of said surfaces thereof, said two adjacent contacts being symmetrically disposed with respect to a plane which is per-

pendicular to said axis and said first rigid contact surface being disposed so that the aforementioned perpendicular plane passes through said first contact surface, and three stationary rigid contact members respectively cooperating with said first and two adjacent contact surfaces.

2. An electromagnetic relay comprising a flat elongated frame, a pair of connecting bars disposed on either side of said elongated frame and having two coaxial apertures elongated in a direction substantially perpendicular to said frame, an elongated flat armature having first and second surfaces and having longitudinal and transverse perpendicular and bisecting axes, pivoting means mounted on said armature and aligned along said transverse axis and engaging said apertures, a C-shaped magnetic core secured to said frame having one end facing said first surface of said armature and the other end facing said second surface of said armature, said first surface facing toward the medial portion of said C-shaped magnetic core and said second surface facing away from the medial portion of said C-shaped magnetic core, electrical means for energizing said core for tilting said armature in one direction about said pivoting pins, restoring means for tilting said armature in a reverse direction, a first rigid contact surface mounted on one of said ends and said first surface

of said armature and disposed substantially along said longitudinal axis of said armature, two adjacent contact surfaces carried by the other of said ends and said second surface of said armature and symmetrically arranged with respect to said longitudinal axis, and three stationary rigid contact members mounted on said frame respectively cooperating with said contact surfaces.

5 3. An electromagnetic relay as set forth in claim 2, wherein said restoring means comprises at least one permanent magnet mounted on said frame.

10 4. An electromagnetic relay as set forth in claim 2, said relay further comprising a second contact surface mounted on said end of said armature which carries said first contact surface and said second contact surface mounted on said second surface of said armature, and a 15 stationary rigid contact member mounted on said frame for cooperating with said second contact surface.
